SIMPLIFIED ADJUSTABLE MAGNETIC HEAD
ASSEMBLY

Edwin Z. Gabriel, Montclair, N. J., assignor to the
United States of America as represented by
the Secretary of the Air Force

Application April 24, 1952, Serial No. 284,194

3 Claims. (Cl. 346—74)

(Granted under Title 35, U. S. Code (1952),
sec. 266)

1

The invention described herein may be manufactured and used by or for the Government for governmental purposes without payment to me of any royalty thereon.

This invention relates to magnetic recorders and more particularly to an adjustable head assembly for magnetic recorders.

In the past it has been the customary practice either to fix the pole piece of the recording head rigidly at the desired distance from the recording medium or to use a differential screw adjusting support for the magnetic head. Since many magnetic recorders require that the magnetic head be adjustably mounted in order to vary the distance of the head with respect to the recording medium the problem of providing a suitable adjustable mount for the head has become more and more serious since the differential screw type of adjustable support requires very precise machining in order to permit fine adjustments of the support.

It is an object of this invention to provide an adjustable head assembly for a magnetic recorder wherein motion of the head with respect to the supporting shaft will be permitted in three directions, namely, rotary, radial and axial.

A further object of this invention is to provide an adjustable head assembly wherein the supporting elements of the head need not be precision machined or cast.

A still further object of this invention is to provide an adjustable head assembly for magnetic recorders wherein two heads or pole pieces may be supported by a single head assembly while still permitting each of the heads to be properly positioned with respect to the recording medium.

The above objects as well as other objects, features and advantages of this invention will be more completely understood with reference to the following description when taken in conjunction with the drawings wherein:

Fig. 1 is a plan view of the adjustable head assembly constructed in accordance with this invention.

Fig. 2 is a top plan view of the adjustable head assembly constructed in accordance with this invention.

Fig. 3 is a cross-sectional view taken along line 3—3 of Fig. 1 showing double head construction.

Fig. 4 is an enlarged fragmentary view of one portion of the split collar adjustable support.

Referring now to the drawings, the magnetic head 9 is suitably mounted on the support bracket 1, as for example by clamping bar 7. The sup-

2

port bracket 1 is internally threaded at 10 and into those threads, screw member 6 is positioned. The support bracket 1 has an opening therein defined by the guide surface 12 and the surfaces 11 and 15. A split collar 2 has surfaces 16 and 17 which mate with the support shaft 8. The split collar has a groove in one portion thereof into which the guide surface 12 slidably fits. The other portion of the split collar has a groove into which a shoe member 5 slidably fits. The shoe member 5 is engaged by the screw 6 and will be moved toward and away from the groove surface of the split collar upon turning of the screw 6. The support member 1 may be made more rigid by incorporating a tie bar 4 as shown in the drawing.

The magnetic head assembly above described may be used with a magnetic recording medium such as a drum or tape 13. In order to permit the above described head assembly to be properly positioned with respect to the recording medium 13 a feeler gauge is placed on the recording surface of the recording medium. With the screw 6 turned such that shoe 5 is loosely engaging the split collar 2, the head assembly is moved so that the head or pole piece 9 rests on the feeler gauge. When the head assembly is so positioned, the screw 6 is adjusted to exert pressure on the shoe 5 which in turn causes pressure to be exerted on the shaft 8 and the guide surface 12 by the split collar 2 and by this pressure the head assembly is frictionally held against movement on the shaft 8. Preferably a lock nut 14 is provided to insure that the screw 6 does not release its pressure against shoe 5.

Referring now to Fig. 3, it will be seen that the magnetic head assembly may consist of two separate heads or pole pieces on either side of the supporting bracket 1.

It is oftentimes desirable to use an electrically nonconductive material for the support bracket 1 in order to minimize the number of parts required for mounting of the terminals 3. Where the magnetic head is of the type used for recording positive and negative pulses on the recording medium, three terminals are usually required for each head.

From the above description it will be apparent that the magnetic head 9 may be adjusted in the rotary and axial directions about the supporting shaft 8 when the screw 6 is loosened and may be adjusted in a radial direction of the shaft 8 by sliding in the grooves of the split collar 2.

Although only a single embodiment of this invention has been illustrated and described, it will

be understood that many changes, additions and omissions may be made without departing from the spirit and scope of this invention.

What is claimed is:

1. An adjustably mounted magnetic recording head assembly comprising, a support bracket having a magnetic recording head mounted thereon, said support bracket having an opening therein which is defined by a guide surface, a split collar having internal surfaces of such shape as to mate with a supporting rod and an external surface to mate with said guide surface and screw means engaging said support bracket and positioned so as to exert force at right angles to said guide surface on the exterior surface of said split collar whereby said support bracket will frictionally engage said split collar and said split collar will frictionally engage said supporting rod when said screw means exerts said force.

2. An adjustable support for a magnetic recording head comprising a support bracket to which a magnetic recording head may be secured, said support bracket having an opening therein, said opening being defined by a guide surface, a split collar having internal surfaces to mate with a supporting rod and an exterior surface to mate with said guide surface and releasable means engaging said support bracket to cause said exterior surface of said split collar to frictionally engage said guide surface and said in-

ternal surfaces of said split collar to frictionally engage said supporting rod.

3. An adjustable support for a magnetic recording head comprising, a support bracket to which a magnetic recording head may be secured, said support bracket having a U-shaped cut away portion, one of the straight sides of said U-shaped surface defining a guide surface, a threaded internal opening in said support bracket extending from the other straight side of said U-shaped surface to the edge of said support bracket, a screw member engaging said threaded internal opening and having a length sufficient to extend into said cut away portion, a shoe member engaged by said screw member when said screw member extends into said cut away portion, a split collar having internal surfaces to mate with a supporting rod and a first external surface to mate with said guide surface and a second external surface to mate with a surface of said shoe member.
